UNITED STATES PATENT OFFICE.

ROBERT REINER, OF WEEHAWKEN, NEW JERSEY.

SHUTTLE.

1,383,484.

Specification of Letters Patent.

Patented July 5, 1921.

Application filed November 8, 1920. Serial No. 422,466.

To all whom it may concern:

Be it known that I, ROBERT REINER, citizen of the United States of America, residing at Weehawken, in the county of Hudson and State of New Jersey, have invented certain new and useful Improvements in Shuttles, of which the following is a specification.

The present invention relates to shuttles 10 for embroidery machines particularly such in which the cover is held in closed position by friction.

With shuttles of this type as hitherto constructed, there is the drawback that the cover 15 while being closed is liable when handled roughly or by unskilled hands to be depressed too far into the shuttle, thereby flattening the delicate bobbin and upsetting the bobbin thread, resulting in the formation 20 of knots and the consequent tearing of the threads during the operation, which results naturally are very objectionable.

The object of my invention is to obviate this drawback by simple means which, as 25 far as I am aware, have never been employed with shuttles.

My invention substantially consists in the novel construction, arrangement and combination of parts as will be hereinafter more 30 fully described and defined in the appended claims.

In the accompanying drawings in which similar reference characters denote similar parts, Figure 1 is a bottom perspective view 35 of my improved shuttle; Fig. 2 is bottom plan view of the shuttle, a part of which is shown in section, and, Fig. 3 is a cross section on line 3—3 of Fig. 2.

a denotes the shuttle, and *b* the cover 40 which, as usual, is hinged at *c* to the rear end of the shuttle, and is so disposed relative to the mouth *a*² of the latter, that when closed one side *b*' thereof at its front part will frictionally engage the inner face of 45 the wall *a*' of the shuttle, while the opposite side *b*² thereof will be free or out of contact with the wall *a*² of the shuttle. This arrangement of a one sided frictional engagement between the cover and the shuttle 50 is necessary, to facilitate the opening of the cover. Owing to a slight resiliency inherent in the cover or hinge *c* thereof, the cover can be pressed laterally to release it from its frictional engagement.

55 In the inner face of the wall *a*', a longi-

tudinally extending incision *d* is provided near the front or the pointed end of the shuttle, whereby a shoulder *e* is produced on which the cover rests when in closed position. It is this shoulder alone that is usually relied upon to limit the extent to which the cover can be depressed when closing the latter. But it has been found that such one sided support or stop is insufficient to prevent a further depression of the cover because the cover after a short use slackens on its hinge and begins to wobble, so that by an increased force it is caused to slip off of the shoulder *e*. This has been a long felt evil but owing to the fact that the shuttle and the space containing the bobbin are limited in size and shape, the solution of the problem has been met with great difficulties.

I have solved this problem by providing 75 in the outer face of the wall *a*² of the shuttle adjoining the free edge *b*² of the cover an impression *f* the bottom *g* of which projects into the interior of the shuttle only an exceedingly short distance. This impression 80 is located at a point where the cover, when pressed sidewise to release it, comes closest to the adjacent wall *a*² of the shuttle so that its free edge *b*² will engage the inwardly protruding wall *g* of said impression. Thus the protuberance *g* can be made 85 of the smallest possible size.

Furthermore by locating the impression or stop at the front end or near the point of the shuttle its presence will not interfere 90 with the bobbin nor thread.

The manipulation of the shuttle will illustrate the advantage of my improvement.

When the bobbin is placed into the shuttle, the cover is depressed into closed position, causing it to snap into the notch *d* and rest on the shoulder *e*. When accidentally the cover in closing is pressed with such force that it will have the tendency to slip off the shoulder *e* the latter will cause it to 100 swing toward the opposite side of the shuttle and to engage with its edge *b*² the protuberance *g*, which will prevent it from being depressed too far into the shuttle and to damage the bobbin.

What I claim is:

1. In a shuttle having an incision in one of its walls and a cover frictionally engaging said wall and resting in said incision, means on the inner face of the opposite wall 110

of the shuttle to limit the extent of the depression of said cover when the latter tends to slip out from said incision.

2. In a shuttle having an incision in one of its walls and a cover frictionally engaging said wall and resting in said incision, an impression near the forward end of the opposite wall of the shuttle at a point where the free side of said cover comes nearest said wall when pressed laterally to release

it, said impression having its bottom protruding into the path of said cover to engage the latter, when tending to slip out from said incision.

In testimony whereof I affix my signature 15 in presence of two witnesses.

ROBERT REINER.

Witnesses:

MARGARET BOLT,
ERICH GROSE.
